BOAT HOUSE DOCK

Richard L. De Golian, 3150 Habersham Road NW,
Atlanta, Ga.

Filed Dec. 23, 1959, Ser. No. 861,650
1 Claim. (Cl. 61—48)

This invention relates, primarily, to floating structures as, for example, a structure supported on pontoons.

More specifically, the instant invention pertains to a device which finds utility as a boat house, dock, marine gas and oil station, and for a variety of other purposes.

One of the primary objects of the instant invention is to provide a pontoon supported boat deck with a substantially coextensive fixed roof.

Another object of this invention is to provide a pontoon type boat dock together with a gangway hingedly connected thereto.

A still further object of this invention is to provide a pontoon supported boat house with means for fixedly anchoring the boat house against drifting.

This invention contemplates, as a still further object thereof, the provision of a boat house of the type generally referred to supra, the boat house being non-complex in construction and assembly, inexpensive to manufacture and maintain, and one which is durable in use.

Other and further objects and advantages of the instant invention will become more evident from a consideration of the following specification when read in the light of the annexed drawings, in which:

FIGURE 1 is a perspective view of the boat house dock constructed in accordance with this invention;

FIGURE 2 is a bottom plan view of the boat house dock shown in FIGURE 1, FIGURE 2 being taken substantially on the horizontal plane of line 2—2 of FIGURE 1, looking in the direction of the arrows;

FIGURE 3 is an enlarged fragmentary detail cross-sectional view, FIGURE 3 being taken substantially on the horizontal plane of line 3—3 of FIGURE 2, looking in the direction of the arrows;

FIGURE 4 is an enlarged fragmentary detail cross-sectional view, FIGURE 4 being taken substantially on the horizontal plane of line 4—4 of FIGURE 2, looking in the direction of the arrows; and

FIGURE 5 is an enlarged fragmentary detail cross-sectional view, partly in elevation, FIGURE 5 being taken substantially on the vertical plane of line 5—5 of FIGURE 3, looking in the direction of the arrows.

Referring now more specifically to the drawings, reference numeral 10 designates, in general, a boat house dock constructed in accordance with the teachings of the present invention. The major constructional elements of this invention are clearly illustrated in FIGURE 1 of the drawings and are seen to comprise a pair of elongated substantially rectangular docks 12, 14 disposed in laterally spaced relation relative to each other, the docks being interconnected centrally of the ends thereof by a substantially rectangular runway 16. A gangway 18, also substantially rectangular in configuration serves to connect the docks with the shore. Reference numeral 20 denotes an elongated corrugated metal roof which extends the full length of the docks 12, 14 and is provided with a pair of remotely disposed overhanging eaves indicated at 22, 24. In a manner to be described below, a plurality of caissons 26 serve both as vertical guide means for the roof 20 and as anchorage means to hold the boat house dock in the preselected site.

The elongated substantially rectangular boat docks 12, 14 are identical in construction and, hence, a description of one is a description of the other. Consequently, only the dock 12 will be herein described in detail, correspond-

2

ing elements of each of the two docks 12, 14 bearing identical reference numerals.

The dock 12 is seen to include a pair of elongated laterally spaced and substantially parallel side frame members 28, 30 channel shaped in cross-sectional configuration. The side frame member 28 includes a pair of laterally spaced and substantially parallel side flanges 32, 34 interconnected by a bight 36. In a similar manner, the side frame member 28 includes a pair of laterally spaced substantially parallel side flanges 38, 40, which are, in turn, connected by means of a bight 42. As is clearly seen in FIGURE 3 of the drawings, the side frame members 28, 30 are disposed in confronting relation relative to each other. Extending transversely across the side frame members 28, 30 in side-by-side relationship are a plurality of elongated substantially rectangular wooden planks 44 which are supported on and secured to the side flanges 32, 38 by conventional means (not shown).

The side frame members 28, 30 are reinforced intermediate their respective ends by means assigned the general reference number 46. The means 46 includes a pair of identical channel shaped members 48 disposed back-to-back with their respective bights 50 engaging one another. From each longitudinally extending side of the bights 50 outwardly project side flanges 52, 54 each having its opposed end portions removed to provide projecting end portions 50A, 50B of the bight 50. The projecting end portions 50A, 50B are rigidly secured, as by welding, within the side frame members 28, 30. As is seen in FIGURE 4 of the drawings, the flanges 52 are aligned with the flanges 32, 38 of the side frame members 28, 30. Planks 44, of course, extend across the reinforcing means 46.

To the outer or exterior sides of the bights 36, 42 of the side frame members 28, 30 are secured a plurality of vertically elongated hollow cylindrical casings 56, the casings 56 being longitudinally spaced from each other along the length of the frame members 28, 30. Reference numerals 56A denote hollow cylindrical casings at the extreme ends of each of the docks 12, 14, the casings 56A being disposed in laterally spaced and confronting relation relative to each other. Each of the casings 56, 56A receive therein the lower ends of a plurality of standards 58, respectively, which are secured against movement relative to each other by means of bolts 60. The other or upper ends of the standards 58 are fixedly secured by conventional means to the corrugated metal roof 20 to support the same over the elongated docks 12, 14 and the interconnecting runway 16. The casings 56, 56A of each of the docks 12, 14 are arranged in opposed pairs and each pair is connected together by tie rods 62. Rigidly secured to and depending from the lower ends of the casings 56A is a second spacer rod 64, the lower ends of the adjacent ones thereof being connected together by means of a tension rod 66 (see FIGURES 1 and 2).

The caissons 26, driven into the bed of the body of water supporting the boat house dock 10 are connected to each of the ends of the docks 12, 14 by means of a metal strap 68 connected to the end planks 44 by means of bolts 70.

As is seen in FIGURE 2 of the drawings, the side frame members 30 are oppositely disposed relative to each other, and centrally of the ends thereof (see FIGURES 3 and 4) is connected to the bights 42, an arm 72 of an angle member 74. The arm 72 of the angle member 74 and its other arm 76 are discontinuous throughout the length of the angle member 74 to serve purposes to be described in detail below.

Reference numeral 78 designates one of a plurality of floats having a substantially rectangular configuration

and being formed of a material lighter than water such as, for example, "styrofoam." Each of the floats 78 is secured to the underside of the planks 44 by means of traversing hanger rods 80 which project through elongated substantially rectangular wood strips 82 which extend longitudinally of the docks 12, 14 in laterally spaced relation relative to each other. The strips 82 engage against the undersides of the floats 78 and are clamped thereagainst by means of nuts 84 threaded on the hanger rods 80.

The runway 16 is seen to comprise (see FIGURE 5) a pair of reversely turned elongated laterally spaced and substantially parallel U-shaped channel members 86, 88 disposed in confronting relation relative to each other. The channel member 86 includes upper and lower arms 90, 92, respectively, interconnected by a bight 94. The channel member 88 comprises upper and lower arms 96, 98, respectively, the latter being interconnected by means of a bight 100. The arrangement of the two channel members 86, 88 is such that the upper surfaces of the arms 90, 96 are coplanar. The remotely disposed ends of the channel members 86, 88 are rigidly connected, by conventional means, to the oppositely disposed channel members 30.

Spaced laterally and inwardly from the channel members 86, 88, and extending substantially parallel thereto are a pair of longitudinally extending support members 102, 104 each of which includes a pair of angle irons having diverging arms 106, 108 and juxtaposed sides 110, 112, the latter being secured together by means of bolts 114 (see FIGURE 5). As is seen in FIGURE 2 of the drawings, the sides 110, 112 of each of the support members 102, 104 extend into and are secured by conventional means to the angle members 74, the arms 106, 108 thereof terminating just short of the arms 76.

Further support means 116 is provided for the runway 16, the last named support means including a pair of substantially U-shaped channel members having their bights 118, 120 disposed in back-to-back relationship relative to each other and bolted together as at 120. The flanges 122, 124, respectively, of the channel members diverge away from each other and the outer sides thereof are disposed in the same plane which contains the outer sides of the arms 90, 96 and the upper sides of the diverging arms 106, 108. As is seen in FIGURE 2 of the drawings, the support means 116 extend transversely between the opposed side frame members 30 and are secured to the angle member 74 by conventional means with the flanges 122, 124 being supported on the arm 76 of the angle members 74. The support means 116 is disposed substantially centrally of the support members 102, 104.

Extending transversely across the upper sides of the channel members 86, 88, the support members 102, 104 and the support means 116 is a plurality of wooden planks 126. Intermediate the ends of the channel members 86, 88, the support members 102, 104 and the support means 116, and disposed in side-by-side relationship are a plurality of floats or pontoons 128 also substantially rectangular in configuration. As is seen in FIGURES 2 and 4, the floats 128 are clamped against the undersides of the immediately adjacent wood planks 126 by means of a plurality of wood strips 130 and hanger bolts 132.

The gangway 18 comprises a pair of elongated, laterally spaced and substantially parallel I-beams 134 having upper and lower flanges 136, 138, respectively. Each bight 140 of the beams 134 terminates in a pair of adjacent ends of the beams in a tongue 142 which is pivotally connected to lugs 144 which project laterally from the bight 36 of the channel member 28. Wood planking 146 extends transversely across the I-beams 134 and is supported on the flange 136 thereof. The free end of the gangway 18 is adapted to rest upon the shore as is illustrated in FIGURE 1 of the drawings or on any other suitable supporting structure.

The boat house dock is completed by connecting elongated strips of a resilient material to the opposed ends of the wood planking 44, 126 and 146 to form fenders designated by the reference numeral 148.

From the foregoing description and through reference to the drawings, it is seen that a substantially H-shaped dock has been described and illustrated which includes two inverted substantially rectangular boat mooring areas A, B and that the dock itself is completely shielded from the sun or inclement weather by a continuous roof.

Having described and illustrated one embodiment of this invention in detail, it is to be understood that the same is offered merely by way of example, and that this invention is to be limited only by the scope of the appended claim.

What is claimed is:

A floating boat house structure including a first dock having a pair of laterally spaced substantially parallel U-shaped channel members disposed in confronting relation and forming a pair of side frame members, planking extending transversely of and supported on one of the arms, respectively, of said side frame members, a plurality of pontoons extending longitudinally of said dock and disposed between said side frame members, means 25 clamping said pontoons to said planking, a second dock including a second pair of laterally spaced substantially parallel U-shaped channel members disposed in confronting relation and forming a second pair of side frame members, second planking extending transversely of and 30 supported on one of the arms, respectively, of said second pair of side frame members, a plurality of second pontoons extending longitudinally of said second dock, second means clamping said second pontoons to said second planking, holding means at each end of each of said docks 35 for holding said docks in laterally spaced and substantially parallel relation relative to each other, said holding means comprising a spacer rod depending from each of said docks adjacent each end thereof, a rigid tension rod extending between and secured to said spacer rods at 40 each pair of adjacent ends of said docks, a runway extending between and rigidly connected to adjacent frame members of said docks, respectively, intermediate their respective ends, a plurality of vertically-elongated casings fixedly secured to the remote sides of the first and said 45 second pair of laterally spaced U-shaped channel members, said casings being disposed in longitudinally-spaced relation, said casings each depending from their respective associated channel members, a standard for each of said casings, said standards each having an end thereof 50 fixedly received within its said casing and its other end projecting upright above said first and second plankings, a roof extending the length of said docks and spanning said runway, said roof being fixedly secured to said other ends of said standards, a ground engaging vertical anchorage member at each end of each of said docks, and means connecting said anchorage members to the immediately adjacent end of said docks and to permit vertical 55 movement of said docks relative to said anchorage members.
